United States Patent Office

Des. 203,948
Patented Mar. 1, 1966

203,948

DENT PULLER

John R. Alexander, R.F.D. 1, U.S. 11,
Harrisonburg, Va.

Filed Apr. 21, 1965, Ser. No. 84,900

Term of patent 7 years

(Cl. D54—13)

FIG. 1.

FIG. 2.

FIG. 1 is a perspective view of a dent puller, as viewed from the front, showing my new design.

FIG. 2 is a bottom plan view of the same.

I claim:

The ornamental design for a dent puller, as shown.
